UNITED STATES PATENT OFFICE.

JOHN H. BARNES, OF NEW HAVEN, CONNECTICUT, ASSIGNOR TO THE
BARNES MANUFACTURING COMPANY, OF SAME PLACE.

DESIGN FOR A KEY.

SPECIFICATION forming part of Design No. 12,134, dated January 18, 1881.

Application filed November 8, 1880. Term of patent 14 years.

To all whom it may concern:

Be it known that I, JOHN H. BARNES, of New Haven, in the county of New Haven and State of Connecticut, have invented a new Design for Key; and I do hereby declare the following, when taken in connection with the accompanying drawing and the letters of reference marked thereon, to be a full, clear, and exact description of the same, and which said drawing constitutes part of this specification, and represents a side view.

This invention relates to a design for that class of keys which are made from sheet metal, commonly called "flat keys;" and the design consists in the configuration of the bow and shank, as shown in the accompanying illustration, and hereinafter described.

The bow has four sides, in substantially the shape of a parallelogram—the one side, *a*, at right angles to the shank, and the two sides *b* at right angles to the side *a*, and parallel to each other. The angles are slightly rounded. The fourth or outer side has a central curve, *c*,

running into the continuation of the curves at the angle, so as to form an indentation, *d*, at 25 the intersection of the curves—that is to say, the outer side is composed of two small semicircles, with an intermediate segment connecting them.

The shank *A* of the key is reduced from the 30 width at the bit end toward the bow, and at the junction of the shank with the bow a semicircular notch, *e*, is made at each side, as shown in the accompanying illustration. The key, however, may be made without this peculiar 35 shape of the shank.

I claim—

The design for key, consisting of the four-sided bow, the angles rounded and the outer side composed of the two semicircles and intermediate segment, as shown in the accompanying illustration.

JOHN H. BARNES.
